(57) **CLAIM**

I claim the ornamental design for the electronic device support, as shown and described.

DESCRIPTION

FIG. 1 shows a perspective view of an electronic device support that is the object of the present invention; FIG. 2 is a left view of the device support of FIG. 1; FIG. 3 is a right view of the support; FIG. 4 is a back view of the device support of FIG. 1; FIG. 5 is a front view of the support of FIG. 1; FIG. 6 is a top view of the electronic device support of FIG. 1; FIG. 7 is a bottom view of the device support; FIG. 8 is a different perspective view of the support; FIG. 9 is a perspective view of the electronic device support thereof but shown in use; and, FIG. 10 is another perspective view thereof.

The electronic device support is a polymer or metallic stand that provides supporting surfaces on which electronic devices can be placed so an observer can conveniently read or watch content displayed on the device screen.

The support also has sets of tabs on which electronic devices can be stowed away when not in use.
